UNITED STATES PATENT OFFICE

132,464

DESIGN FOR A PORTABLE STRUCTURE

Louis Edelman, East Cleveland, Ohio

Application January 13, 1942, Serial No. 105,172

Term of patent 14 years

To all whom it may concern:

Be it known that I, Louis Edelman, a citizen of the United States, residing at East Cleveland, in the county of Cuyahoga and State of Ohio, have invented a new, original, and ornamental Design for Portable Structures, of which the following is a specification, reference being had to the accompanying drawing, forming a part thereof, in which:

The rear side of the structure is plain except for necessary doors and windows.

I claim:

The ornamental design for a portable structure, as shown and described.

LOUIS EDELMAN.
